MARKING DEVICE

Filed Aug. 6, 1927

FIG. I

FIG. II

INVENTOR
F. R. HASELTON

BY *J. S. G.*
ATTORNEY

UNITED STATES PATENT OFFICE.

FREDERICK R. HASELTON, OF ST. PAUL, MINNESOTA.

MARKING DEVICE.

Application filed August 6, 1927. Serial No. 211,093.

This invention relates to marking devices and is herein illustrated as embodied in a device for use in indicating the location of a submerged object.

5 It is a matter of common knowledge that an object sinking in water, in which there are tides and currents, does not descend vertically to the bottom but drifts until it finally comes to rest at a point off-set from that 10 at which it entered the water. Owing to this tendency on the part of sinking objects as well as their likelihood of settling in the soft muddy bottom of a stream or lake, the recovery of articles accidentally dropped 15 into such bodies of water is very difficult, and it is not uncommon that articles so submerged are never recovered. Similarly valuable objects are often lost by falling in water that is of great depth. Examples of 20 such losses of articles are to be found in the practice of outdoor sports, such as fishing, hunting, and canoeing where rifles, tools, fishing rods, etc. are apt to be dropped into a lake or stream, and also in marine operations 25 where valuable articles such, for example, as the payroll of a ship, are transferred by means of a small boat from shore to the vessel at a time when the sea is rough.

With the foregoing considerations in view, 30 the present invention has for an important object thereof the provision of a marking device which may be readily affixed to any object to serve in indicating the position of the object in the event of its submersion.

35 If a device of this character is employed in connection with articles used in outdoor sports, such as fishing and hunting, it will be appreciated that the device must be compact and so arranged that it may be affixed 40 to the articles so as not to interfere with their ready manipulation. Accordingly, the invention has for an important feature thereof the provision in a device of this character of a shell for enclosing the mechanism 45 of the marking device, said shell being compact and adapted to be fitted snugly to an article such as a gun, tool, out-board motor fishing rod, etc. In the illustrative embodiment of the invention the shell is provided 50 with open ends, one of which is adapted to receive the marking mechanism, and the other of which is adapted to be fitted into or over the article in connection with which the marking device is used.

55 Another feature of the invention consists in the provision of a closure for retaining

normally the marking mechanism within the open ended shell, said closure being so constructed and arranged as to permit escape of the marker from the shell upon submersion 60 of the marking device. In the illustrative embodiment of the invention this feature is carried out by the provision of a dissolvable or water soluble disk which may be inserted into the open end of the shell, submersion 65 of the shell causing the disk to dissolve, thereby permitting free emission of the marker.

As shown in the illustrative embodiment 70 of the invention, the marking device comprises a spool or reel upon which is wound a thread having one of its ends secured to the reel and its opposite end connected to a marker made from material which will float, such, for example, as cork, wood, etc. To 75 insure the discharge of the float from the casing upon submersion of the article to which the casing is attached, there is provided a spring arranged to press against the side of the marker opposite to the dissolvable disk, and in the operation of the device, upon the disk becoming partially dissolved, the spring acts to force the float suddenly free and clear of the casing within 80 which it has been located, whereupon it 85 arises to the surface of the body of water, and being connected with the casing by means of the thread, serves distinctly to indicate the position of the submerged article, and further provides a convenient means 90 for recovering the article without requiring the search to be extended beneath the surface of the water.

Other features and objects of the invention 95 will become apparent from a reading of the following description in the light of the accompanying drawings in which,

Fig. I is a view in section showing the mechanism of the device, and

Fig. II is a view in section taken on the 100 line II-II of Fig. I.

As shown in the drawings, the numeral 10 indicates a cylindrical shell or container provided with open ends and having formed centrally of its length an integral dividing 105 wall 12. In the illustrative embodiment of the invention one of the open ends of the shell 10 is rendered expansible by the provision of a series of longitudinally extending slots 14, and is provided with a plurality of clamping fingers 16, by means of which slots 110 and fingers the shell 10 may be positioned

and clamped firmly upon the extremity 18 of a fishing pole, a tool handle, etc.

A hollow cylindrical cup or casing 20 is formed integrally with the dividing wall

5 12 and is adapted to receive and to support a spool or reel 22 upon which is wound a fastening 24, which is illustrated in the form of a thread having its inner end secured to a spool securing screw 26, and its outer end 10 passing through and knotted against displacement from a float or marker 28.

To the end of preventing accidental discharge of the marker 28 from the shell 10, there is provided means to retain the marker 15 within the shell. As illustrated, the retaining means comprises a disk, or closure 30 inserted within a groove formed within the open end of the casing. It has been found that a highly satisfactory type of 20 closure is one made from a dissolvable, or water soluble substance, such for example as gelatine, etc. By means of such a provision, submersion of the device causes the closure to dissolve thereby permitting free escape of 25 the marker.

The marking device may conveniently be provided with means, such as a spring 32 for forcibly and suddenly projecting the float 28 from the casing upon the dissolving 30 of the seal 30. Such an arrangement insures the successful operation of the device upon the water into which the device has been submerged, dissolving the disk 30.

While the invention has been illustrated 35 and described herein as embodied within a shell for use in connection with cylindrical objects it is to be appreciated that the invention may be embodied in differently shaped containers for use in connection with various 40 other objects. For example the fingers 16 could be omitted and the shell inserted into the heel-plate of a rifle or shot-gun, or a device of this character could be made in a flattened form and embodied in the side of 45 a box, sack, etc.

Having thus described my invention, what I claim as new and desire to secure by Letters Patent of the United States is:

1. A marking device comprising a hollow 50 cylindrical shell having a dividing wall located substantially midway of the length of said shell, slots formed in one of the ends of said shell to render said end expansible, means located adjacent to said slots for securing the shell to an external object, and a marker located in the opposite end of the shell, said marker being normally restrained within the shell but permitted to escape upon submersion of the object to which the 55 shell is secured.

2. A device for marking the locality of a submerged article comprising, in combination, a container having an open end, a marker located within said container, and a 60 closure for the open end of the container,

said closure being made of a water soluble substance dissolvable to permit release of the marker from the container upon submersion of the latter.

3. A device for marking the location of a submerged article comprising, in combination, a container having an open end, a marker located within said container, and a gelatinous closure for the open end of the container, said closure being dissolvable to 75 permit release of the marker from the container upon the submersion of the latter.

4. A device for marking the location of a submerged article comprising, in combination, a container having an open end, a marker located within said container, fastening means extending between said marker and said container, and a closure for the open end of said container, said closure being made of a soluble substance to permit discharge of the marker from the container 85 upon the submersion of the latter.

5. A device for marking the location of a submerged article comprising, in combination, a shell having an opening therein, a 90 marker located within the shell, means tending normally to project the marker through the opening in the shell, and a closure for said opening arranged to restrain the marker within the shell, said closure being operative 95 upon submersion of the shell to permit discharge of the marker from the shell.

6. A device for marking the location of a submerged article comprising, in combination, a container having an opening formed 100 therein, a marker positioned normally within said container, a fastening having one of its ends secured to said marker and its opposite end secured to a supporting reel located within the container, a dissolvable 105 closure for the opening in said container, and resilient means tending normally to press the marker against the dissolvable closure in such a manner that upon dissolution of the closure the marker is projected forcibly 110 from the container.

7. A marking device comprising a shell adapted to be affixed to an external object, a marker secured within said shell, a water soluble substance retaining normally the 115 marker within the shell, and operative to release the marker upon the submersion of the article to which the shell is affixed.

8. A marking device comprising a hollow shell, means to secure said shell to an external object, a marker within said shell, and a dissolvable seal arranged to restrain normally the marker in a position within the shell and operative to release the marker upon the submersion of the object to which the marking device is affixed, and means to eject forcibly the marker from the shell upon the release of the former.

9. A device for marking the location of a submerged article comprising, in combina- 130

tion, a container, a float, and a soluble seal adapted normally to restrain the float within the container and being operative upon submersion to permit escape of the float from the container.

10. A device for marking the location of a submerged article comprising, in combination, a container, a float located within said container, a fastening arranged to extend

between the float and the container, and a soluble seal adapted normally to restrain the float within the container and operative to permit discharge of the float upon submersion of the container.

In testimony that I claim the foregoing I ¹⁵ hereunto affix my signature.

FREDERICK R. HASELTON.
